FOREIGN PATENT DOCUMENTS

EM 006863635-0002 * 9/2019

Primary Examiner — Lilyana Bekic

(74) Attorney, Agent, or Firm — True Shepherd LLC;
 Andrew C. Cheng(57) **CLAIM**

The ornamental design for portable oral irrigator, as shown and described.

DESCRIPTION

FIG. 1 is a perspective view of a portable oral irrigator showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines are for the purposes of illustrating portions of the portable oral irrigator and form no part of the claimed design.

1 Claim, 8 Drawing Sheets(56)
